UNITED STATES PATENT OFFICE.

HENRY S. HALE, OF PHILADELPHIA, PENNSYLVANIA.

DESIGN FOR A CAR-SEAT FRAME.

SPECIFICATION forming part of Design No. 27,871, dated November 16, 1897.

Application filed July 28, 1897. Serial No. 646,269. Term of patent 14 years.

To all whom it may concern:

Be it known that I, HENRY S. HALE, of the city and county of Philadelphia, State of Pennsylvania, have invented a new and useful Design for Car-Seats, of which the following is a specification.

My design is illustrated in the accompanying drawings, in which—

Figure 1 shows a perspective view of a car-seat frame embodying my design, and Fig. 2 is a horizontal transverse sectional view of the same on the line $x x$ of Fig. 1.

A is the base, which is of oval or oblate or equivalent shape, having a greater longitudinal than transverse axis.

B is the pedestal, extending upward from the base A to the upper portion of the side frame C.

The pedestal B is enlarged at the bottom where it springs from the base A and has at 20 this part an oblate or oval cross-section, as indicated by the dotted line in Fig. 1.

The essential feature of the design resides in the elongated or oblate base A and the pedestal springing therefrom.

Having now described my invention, what I claim as new, and desire to secure by Letters Patent, is as follows:

The design for a car-seat frame substantially as herein shown and described.

In testimony of which invention I hereunto set my hand.

HENRY S. HALE.

Witnesses:

WM. M. NORCROSS,
GEO. H. RAPSON.
